UNITED STATES PATENT OFFICE

CHARLES S. BUSHNELL, OF ROCHESTER, NEW YORK, ASSIGNOR TO GENERAL RAILWAY SIGNAL COMPANY, OF ROCHESTER, NEW YORK

AUTOMATIC TRAIN-CONTROL SYSTEM

Original application filed May 18, 1921, Serial No. 470,592. Divided and this application filed February 25, 1927. Serial No. 170,847.

This invention relates to automatic train control systems for railroads, and more particularly to the car equipment of such systems, and is a division of application No. 470,592 filed May 18, 1921.

When a system of automatic train control is applied to a train, there is a natural tendency for the engineer to rely upon this system. If the engineer has confidence in the proper performance of the automatic apparatus, he may perhaps be more lax in his observance of the usual block signals, since he will feel that the automatic devices will in some way give a special warning or apply the brakes automatically in case of danger. It is considered objectionable, however, to take away the vigilance of the engineer, because modern block signal systems are very reliable and efficient, and engineers as a rule are highly trained, experienced and careful operators, so that if the engineer becomes negligent in observing the signal indications or in acting upon them, there is sacrificed a large proportion of the safety of train operation at present obtained by the signal system and the care with which the engineers ordinarily observe and obey the signals. It is evident that the ultimate safety of the train is increased if the automatic train control system is supplementary to the block signal system and the vigilance of the engineer, rather than as a substitute therefor; and if the engineer can be encouraged or forced to observe and act upon the indications of the trackway signals, a serious accident can result only when signal system, the engineer, and the train control apparatus all fail at the same time.

With these considerations in mind, one object of the present invention is to provide a system of automatic train control in which a suitable penalty is automatically enforced if the engineer fails to observe a caution or stop signal, and fails to take some appropriate action in recognition of such unfavorable signal indication. If the engineer observes this indication and acts accordingly, the penalty will not be enforced; and the engineer is thus encouraged to observe and act upon the signal indications. According to the present

invention the penalty in question consists in causing an automatic brake application, or in imposing some suitable form of control, which persists until a reset device is manually operated. This reset device is preferably made accessible only from the ground or is arranged in some other way so that it cannot be used without great trouble and annoyance, and is also protected so that it cannot be maliciously fastened down, or manipulated in such a way as to avoid the penalty and defeat the purpose of the invention.

This invention is in the nature of an improvement upon the system disclosed and claimed in the application of W. K. Howe, Ser. No. 47,110, filed July 30, 1925; and the patent to Howe No. 1,551,515 dated August 25, 1925.

In the accompanying drawings;

Fig. 1 is a diagrammatic view of one arrangement of trackway circuits applicable to the present invention;

Fig. 2 is a diagrammatic view of a car equipment, the parts and circuits being shown more particularly with the object of making the functions and mode of operation easy to understand, than with the idea of showing the precise construction and arrangement of parts preferably employed in practice; and,

Fig. 3 illustrates a modified wiring arrangement and construction of the car equipment.

Referring to Fig. 1, the track rails 1 of the railroad track are divided by insulated joints 2 into blocks in the usual way, one block N with the adjacent ends of two other blocks M and O being shown. The parts and circuits associated with the several blocks are the same, and for convenience these will be given like reference characters with distinctive exponents. Each block is provided with the well-known normally closed track circuit commonly used in block signal systems, comprising a track battery 3 and a track relay 4. The usual trackway fixed signals S are illustrated conventionally, and since they may take various forms, such as semaphore signals or color light signals, and may be controlled in any of the well-known ways, no attempt has been made to illustrate their con-

trol circuits and devices, it being understood that these signals will give the usual clear, caution, and stop indications and will be obeyed in accordance with the rules in force on the particular railroad.

In the particular embodiment of the invention illustrated, it is assumed that the transmission or communication of the desired controlling impulses or influences from the trackway to the moving trains for governing the automatic apparatus thereon in accordance with traffic conditions, is accomplished inductively, that is, through an intervening air gap. While this inductive type of impulse transmitting means may take any one of various well-known forms, there is illustrated an arrangement comprising a track element T.

The track element T comprises in general a U-shaped yoke or core 5 of magnetic material, with coils 6 thereon. The coils 6 are wound and connected in series in such a way that the electro-motive-forces generated in the respective coils by flux passing through the yoke 5 are cumulative or additive. These track elements T may be located and controlled in various ways, dependent upon traffic conditions ahead, but in the particular arrangement shown in Fig. 2, a track element T is located at the entrance to each block, a short distance in the rear of the insulated joints 2, the normal direction of traffic being from left to right, as indicated by the arrow. The coils 6 of this track element T are connected in series in a normally closed circuit of low resistance, including the front contact of a line relay D. The energizing circuit for the line relay D includes a front contact of the track relay 4 of the corresponding block, and a front contact of the track relay 4 of the next block in advance. Thus, the coils 6 of the track element T at the entrance to a given block are in a closed circuit under clear traffic conditions, but are open-circuited under caution or stop conditions, that is, when the corresponding block or the next block in advance is occupied. These track elements T may be located crosswise of the track between the track rails as shown, or lengthwise, between or outside of either track rail, and in other ways, provided the car element is disposed accordingly.

The car element Y, see Fig. 2, comprises a similar U-shaped core or yoke 7 of magnetic material and is supported in some suitable manner from the frame of the locomotive or other vehicle, so as to pass directly over the track element T, as shown in Fig. 2. The air gap between the pole pieces of the track element T and the car element Y is preferably made as short as equipment and roadway clearances will permit. On one leg of the 7 is a coil 8 conveniently termed the primary coil and on the other leg of said yoke is an

other coil 9, conveniently termed the secondary coil.

In connection with the car element Y, there is preferably employed an electron amplifying relay of the thermionic or vacuum bulb type, commonly known as an audion, and which will be referred to by that name as a matter of convenience. This audion, being well-known in the art, is illustrated conventionally, and comprises a filament F, a grid 75 G and a plate P.

The audion controls a car relay R. The features of construction of this relay R adapting it for use in a train control system of the type shown forms no part of the present invention, and this relay is shown conventionally.

The train control apparatus, which acts to apply the brakes or in some other way govern the train with safety, may take various forms, and since its particular construction forms no part of the present invention, this apparatus has been illustrated conventionally as a device K. This device, shown in the form of an electro-magnetic valve, may 90 act to vent the train pipe and apply the brakes directly, or govern the operation of some other form of speed regulating or brake controlling mechanism. This device K is normally energized, and is set into operation 95 when de-energized.

In connection with certain forms of the invention, it is necessary to provide the device K with contacts which are broken when said device is de-energized. In the conventional construction illustrated in Fig. 2, the core or plunger of the device K carries an insulated disc 10 which engages suitable fixed contacts (shown conventionally as arrows) and thus completes a circuit through said contacts when the device K is energized. When the device K is de-energized, its core or plunger is moved by a spring, air pressure or the like, to move the disc 10 out of engagement with its cooperating fixed contacts, thereby breaking the circuit through said contacts.

In connection with the invention there is preferably employed a suitable cab signal or indicator, and while this indicator may be a light, bell, or the like, it has been illustrated 115 as an electrically controlled air whistle W, which is constructed so as to sound the whistle when its controlling magnet is energized.

The reset switch or button Q is shown conventionally as spring plate or key 11 which normally engages a fixed contact and can be moved from engagement therewith against another contact. This reset switch Q is in practice enclosed in a suitable protecting casting, which may be sealed or locked, or placed 125 so as to be accessible only from the ground, or in some other way arranged so that it can not be operated by the engineer without bringing the train to a stop, or without great inconvenience, or without calling in the as- 130

sistance of someone else, the purpose being to make the operation of this reset switch Q so objectionable to the engineer that he will voluntarily observe and obey the signals to avoid the necessity of such operation. The hold-off switch or device H is arranged in the cab in a convenient position to be operated by the engineer; and to prevent its improper manipulation, there is provided associated mechanism which prevents the device being held closed or fastened down. A hold-off device of this character is disclosed in a generic form in the Howe application above mentioned, and it is to be understood that no claim is made here to the generic form of the invention disclosed in the said application.

The circuit connections between the audion, the relay R, and the control device K are subject to considerable modification in practice, but since any form of connections suitable for causing operation of the relay R when the car passes an active track element, is applicable to the present invention, only one typical arrangement has been illustrated. The filament F of the audion is heated by the battery A. The grid G is connected in circuit with the secondary coil 9 and the battery C by wires 38 and 39, so that electro-motive-forces induced in the secondary coil will vary the grid potential. The plate P is connected in circuit with the relay R, a front contact thereof, and the batteries B and C. Referring to Fig. 2 this plate circuit may be conveniently traced as follows:—commencing at the positive terminal of battery B, wires 40, 41, 42, front contact 43 of relay R, wires 44 and 45, relay R, and wire 46 to plate P.

The primary coil 8 is normally energized from batteries B and C through the train control device K and the front contact 43 of the relay R, this circuit being traced as follows:—commencing at battery B, wires 40, 41 and 42, front contact 43 of relay R, wires 44 and 47, reset switch 11 and its closed contact, wire 48, device K, wire 49, primary coil 8, and wire 51 to the battery C.

Operation.—The battery C normally produces a positive potential upon the grid G with respect to the average potential of the filament F, and thus permits current to flow in the plate circuit and maintain relay R energized. The current through the primary coil 8 produces a magneto-motive-force tending to send flux through the car yoke 7, this flux passing in part through the legs of said yoke and in part through leakage paths. The yoke 7 may be said to constitute a partial magnetic circuit with an air gap of relatively high reluctance.

Assume that the car passes over a track element T having its coils 6 open-circuited, corresponding to dangerous traffic conditions ahead, that is, when a stopping impulse should be transmitted. The track element in

this condition presents in effect a magnetic loop for the yoke 7 on the passing car, and acts to complete the partial magnetic circuit on the car and change its reluctance, the reluctance decreasing from a normal to a minimum, and then back to normal, as the car approaches and recedes from the track element. This change in reluctance varies the flux passing through the secondary coil 9, thereby inducing an electro-motive-force in said coil, first in one direction and then in the other. One half of this wave of induced E. M. F. in the secondary coil 9, either the first or second half depending upon the connections, opposes the voltage of the battery C and reduces the potential on the grid G. The normal potential on the grid G being thus decreased, the current flowing in the plate circuit through the relay R is likewise decreased, and the parts are so proportioned and adjusted that the current in the relay R is reduced in this way below the amount required to hold its front contact 43 closed. When the front contact 43 opens, the train control device K is de-energized, and the circuit through relay R is also broken at its contact 43, with the result that said relay can not again pick up when the grid potential again becomes normal.

Suppose that the coils 6 of the track element T are included in a closed circuit of low resistance, corresponding to clear traffic conditions. When the car element Y passes over a track element in this clear or inactive condition, the relay R is not operated, because the coils 6 on the track element oppose or choke back the passage of flux through the yoke 5 due to the counter-electro-motive-forces induced in said coils, with the result that there is little change in flux through the secondary coil 9 and the relay is not operated.

The operation so far described is that which is characteristic of the type of system illustrated, this particular system being merely illustrative of one suitable for the application of the present invention, and being disclosed and claimed in other applications. Arrangements to prevent improper operation of the car equipment by track rails or other masses of iron along the track, and various other expedients that may be necessary or desirable in a complete system, are not material to the present invention, and being fully disclosed in other applications, are not herein illustrated. Further, the operation so far described does not take into consideration the action of the hold-off device H, the reset switch Q, and associated parts constituting the subject-matter of the present invention.

As previously explained, the purpose of the present invention is to provide an arrangement for enforcing vigilance on the part of the engineer in observing and acting upon the indications of the fixed signals. The engineer is supposed to watch out for the va-

rious fixed signals S, and if one of these signals indicates caution, it is intended that he should operate the hold-off device H while passing the corresponding track element T, this act being in recognition of the cautionary indication of the signal and an acknowledgement that there is another train a short distance ahead. It is assumed that if the engineer makes such a positive movement, he fully appreciates the existence of danger and may be relied upon to slow down the train or take such action as is necessary to avoid a collision.

Consequently, if the engineer is alert and operates the hold-off device at the proper time in recognition of a caution signal, it is unnecessary to take the control of the train out of his hands or apply the brakes at once; and the preferable arrangement of circuits is such that timely operation of the hold-off device H prevents, in some of the ways hereinafter described, the effective action of the track element upon the train control device K. If the engineer is not alert, however, and due to negligence or any other cause fails to see or read correctly the signal indications, he will not operate the hold-off device at the proper time, and then the train control apparatus K will be automatically set into operation as the train passes over the active track element, thereby slowing down the train and avoiding a collision. Further, the construction is such that the control exerted by said apparatus upon the train will be maintained until the reset switch Q is operated. If this reset switch Q is accessible only from the ground, so that the train must be stopped before it can be actuated, or if operation of this switch is made difficult or objectionable in some other way, the engineer will naturally prefer to operate the hold-off device H in recognition of each caution signal, rather than be subjected to the special trouble, annoyance, or publicity of actuating the reset switch Q. It may be noted here that the penalty, being self-inflicted, so to speak, and concurrent with the default, will naturally have more influence than any subsequent discipline, although it is evident that a recorder or similar device may be used in conjunction with the system shown and described to provide a check upon the way in which the engineer performs his duties.

Referring now to the specific arrangement of circuits and devices for preventing effective action of an active track element upon the train control device K when the hold-off device H is properly operated, and for imposing a penalty when such device is not properly operated, Fig. 2 shows an arrangement in which operation of the handle 12 of the hold-off device H to close contacts 16-18 establishes a circuit which prevents de-energization of the device K when the front contact 43 of the relay R opens. This hold-off

circuit may be traced as follows:—commencing at battery B, wires 40 and 52, whistle W, wire 53, normally closed contacts 25-26 of the hold-off device H, contacts 16-18, wire 54, normally closed contacts 10 of the device K, wire 55, switch 11 and its closed contact, wire 48, device K, wire 49, primary coil 8 and wire 51 to the battery C and back to battery B. In effect this circuit comprises in part a shunt around the front contact 43 of the relay R, so that although said front contact opens, the device K is maintained energized.

If the engineer operates the hold-off device H the whistle W is sounded when the front contact 43 of the relay R opens, said front contact, together with wires 41, 42, 44 and 47 constituting a low resistance shunt around the circuit portion comprising wire 52, the winding of the whistle W, 53, 25-26, 16-18, 54, 10 and 55 and depriving the winding of whistle W of effective current until said front contact 43 opens. The whistle W thus serves to indicate that the track element has been passed, and that the hold-off device H may be released. Also, the sounding of the whistle W signifies that the train control equipment is working properly, and that an automatic operation of the device K would have occurred if the hold-off device had not been operated. When the relay R opens its front contact, this contact will be at once closed as soon as the normal current again flows in the plate circuit, because the front contact of said relay is shunted by the hold-off contacts 16-18 through the whistle W, the winding of the whistle W being made in practice of low enough resistance to permit the relay R to pick-up with said winding in series therewith.

If the engineer does not operate the hold-off device H at the proper time, the relay R drops and de-energizes the device K, imposing the desired control upon the train, and also opens the contacts 10 of said device so that subsequent operation of the hold-off device H is not effective to restore the relay R. The relay R can only be restored by operating the reset switch Q. When the reset switch Q is actuated to close its normally opened contacts, the relay R is energized by a circuit which may be traced as follows:—commencing at the battery B, wires 40, 41 and 56, switch 11, wires 47 and 45, relay R and wire 46 to the plate P. When relay R is thus picked up, it is held up through its own front contact 43 and the switch Q may be restored to normal.

It will be noted that when the switch Q is actuated, it breaks the energizing circuit for the device K, so that unless restored to the normal position, the train is not released from the control imposed by the device K. Thus, the reset switch Q is protected against improper manipulation, and can not be fastened down, otherwise the train control device K

will be operated and prevent the usual train movement.

In the form shown in Fig. 2, the normally closed contacts 25—26 of the hold-off device H are included in the wire 53 of the hold-off circuit and are also included in series with the normally opened contacts 16—18 of said hold-off device. The cam 22 of this acknowledging device H is biased in a clockwise direction, but is held against rotation by the pin 23 thereof engaging the handle 12, the spring 15 being sufficiently strong to overcome the force of the bias of cam 22. If the handle 12 is held down, the cam 22 rotates in a clockwise direction at a restricted rate determined by a suitable time controlled device, more specifically described in the parent application. If the engineer holds down the handle 12 too long, the contacts 25—26 open, for reasons apparently from the shape of the cam 22, rendering the device H ineffective and causing automatic operation of the device K at the next active track element T. In other words, while the engineer may fasten down the handle 12 of this hold-off device without immediate penalty, this act will at the same time destroy the effectiveness of said hold-off device and consequently make it useless to fasten down the handle 12. In short, the engineer must operate the hold-off device at each signal and at the time he is passing that signal, otherwise an automatic operation of the train control device K will result.

Fig. 3 shows a modified arrangement of the parts and circuits constituting the invention, in which the operation of the hold-off device H prevents effective action of the cautionary impulse by maintaining the control relay R energized. In this modified arrangement, when the handle 12 is moved down and contacts 16—18 are closed, the relay R may be maintained energized independently of the decrease in current between the plate and filament of the audion by an auxiliary energizing circuit as follows: commencing at an intermediate tap of the battery B, wire 70, adjustable resistance 71, wire 72, contacts 16—18, wire 73, contacts 25 and 26, wire 74, relay R, wires 45 and 44, front contact 43, wires 42 and 40 to the end tap of the battery B. The voltage of the section of the battery B included in this circuit, together with the resistance 71, is proportioned with regard to the resistance of the audion between the plate and filament, so that the current supplied to the relay R corresponds substantially with its normal working current when governed by the audion.

The modified circuit arrangement shown in Fig. 3 has the same general characteristics of operation that have been described. As the engineer approaches a caution signal, he may press down the lever 12 and close contacts 16—18, thereby preventing the relay R from dropping as the car element T passes over

the track element T in the active stopping condition. If the engineer does not make proper and timely operation of the hold-off device H, the relay R is de-energized, and the train control device K set into operation in the regular way. After the relay once becomes de-energized, and its front contact 43 opens, the reset switch Q must be actuated before the train control device K can be re-energized.

The modified form of the invention shown in Fig. 3 is exactly the same as that shown in Fig. 2, except that a different form of hold-off or acknowledgement arrangement is provided. In Fig. 3 the elements 52, W, 53, 54, 10 and 55 of the hold-off means shown in Fig. 2 have been omitted, and the normally closed contacts 25—26 and the normally opened contacts 16—18 of the hold-off device H have been employed to provide a distinct circuit for maintaining the relay R energized irrespective of the action of the amplifying device F, G, P upon passage of a train by a control point. It will be noted that upon operation of the handle 12 and for a predetermined period of time thereafter both pairs of contacts 16—18 and 25—26 are closed, and the following hold-off circuit is completed:— starting at the plus side of battery B, wires 40 and 42, contact 43, wire 44, winding of relay R, wire 45—74, contacts 26—25, wire 73, contacts 18—16, wire 72, resistance 71, wire 70 back to the midpoint of battery B. The closure of this circuit maintains the relay R energized even though the plate circuit in the amplifier drops to zero.

This modified form of Fig. 3 has its normally closed contacts 25—26 included in series with its normally open contacts 16—18, similar to the arrangement shown in Fig. 2 of this application, and except for the change of location of the normally closed contacts 25—26 this modified form (Fig. 3) is the same as original Fig. 8 of the parent application.

Having thus shown and described my invention, it is to be understood that my invention is not limited to the specific arrangements shown and described.

What I claim is:—

1. In an automatic train control system, an electromagnetic brake control device on a vehicle, a relay governing said device, traffic controlled means for controlling the relay, and manually operable means adapted to prevent operation of the relay and having a limited time of effective operation, such means including normally open and normally closed contacts in series.

2. In a train control system; cooperating track and car-carried elements; a device for applying the car brakes when initiated; stick controlling means for initiating said device and normally affected by trackway influences to initiate said device; and acknowledging means, including normally open and normally

closed contacts in series with each other, operable to prevent the said affecting of the controlling means by said trackway influences, said acknowledging means including means 5 automatically operable after a predetermined time interval from operation thereof, to cause opening of the normally closed contacts; and reset means, when operated, initiating said device and closing a pick up circuit for said 10 stick controlling means.

3. In an automatic train control system of the intermittent inductive type, the combination with a control relay on the car connected in a stick circuit including its own front contact, of trackway means at spaced control points along the trackway for inductively through an intervening air gap de-energizing said control relay upon passage of said car under adverse traffic conditions, an acknowledging device including normally closed and normally open contacts constructed when operated to close the normally open contacts immediately and open the normally closed contacts a predetermined interval of time 20 after such operation, and a shunting circuit for preventing said trackway means de-energizing said control relay including said normally open contacts said normally closed contacts and a signal in series, whereby said 25 signal is rendered active upon the reception of a control influence from the trackway and said control relay is maintained energized if said acknowledging device has been operated.

In testimony whereof I affix my signature.
